F. G. NICOLAUS

SLIDING DOOR FOR STOVES

Filed Dec. 18, 1924

FIG. 1.

UNITED STATES PATENT OFFICE.

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY.

SLIDING DOOR FOR STOVES.

Application filed December 18, 1924. Serial No. 756,755.

To all whom it may concern:

Be it known that I, FREDERIC G. NICOLAUS, a citizen of the United States, residing at Cleveland, in the county of Cuyahoga and

5 State of Ohio, have invented certain new and useful Improvements in Sliding Doors for Stoves, of which the following is a specification, reference being had therein to the accompanying drawing.

10 This invention relates to improvements in sliding doors for stoves, and is particularly intended for closing the space below the gas burners though, of course, it may be used in any position desired.

15 The primary object of this invention is the construction of a very simple way of applying a vertical door and opening and holding it open by swinging it upward into a horizontal position, and then pushing it 20 in whereby it will be held in its open position.

25 A further object of the invention is providing the frame of the stove with a horizontal slot to receive the edges of the door and providing the inner end or top of the door with means for catching the wall of the slot and maintaining the door in its closed position.

30 A further object of the invention is providing the frame of the door with two horizontal slots adapted to receive opposite edges of the door and bending the upper ends of the edges of the door inward, whereby they catch on the lower walls of the slots 35 and maintain the door in a closed position, at the same time enabling the door to be swung outward and open and, when desired, pushed inward and maintained in its open position.

40 Other objects of the invention will appear from the following description.

In the accompanying drawings:

Figure 1 is a perspective view of a stove showing my improved door construction applied to the space under the burners.

45 Fig. 2 is an enlarged detached perspective view showing one side of the frame of the stove and the corresponding edge of the door in closed position.

50 Fig. 3 is an enlarged detached perspective view of one edge of the door and the corresponding part of the stove frame, the parts shown in separated relation.

Fig. 4 is a view showing the L-shaped frame and one leg of the L-shape shorter 55 than the other.

Fig. 5 is a sectional view showing the door in its open position.

Fig. 6 is a similar view showing a horizontal run-way provided for the door. 60

In Fig. 1 a stove A is shown to which my improved door B is applied. This door consists of a central portion 1, which is surrounded by an L-shaped frame 2. The door B has its edges turned inward, as at 3, and 65 is secured to one leg of the L-shaped frame 2 by bolts 3², which pass through them. It will be noted that the door is located to close and open the space which lies under the place 4 occupied by the horizontal 70 burners (not shown). Ordinarily this part of the stove is open, but providing it with a door it is converted into a warming oven.

The door B consists preferably of sheet metal, which may or may not be enameled 75 and its vertical edges 5 slide in horizontal slots 6, formed in the sides 7 of the frame of the stove. The upper ends of the leg 5, of the L-shaped frame 2, are bent into hook form 8, whereby when the door is in its vertical closed position, the hook catches on the lower wall of the slot 6, and sustains the door in its vertical position.

A suitable handle 9 is located at the lower edge of the door B, whereby it may be swung 85 outward and caused to slide inward until its handle 9 strikes the tray 10, which is placed below the burner space. This tray 10 is supported in a run-way 11, whereby it is removable for the purpose of cleaning it. As 90 shown, the center portion of the door is also bent inward in hook-shape, as shown at 12, though this hook does not perform any function in respect to the door in its several positions, except it makes a finish for its 95 upper edge.

If desired, a run-way 13 may be provided in which run-way the door can be slid and supported in any desired position. However, this adds additional expense and is not 100 at all necessary.

The leg 2' of the L-shaped frame 2, has its upper end 3' cut-away so that the leg 2 extends beyond the leg 2' and is formed into the hook 8. 105

From the above description, it will be ob-

vious that the central portion B of the door is surrounded by the L-shaped frame 2. However, I do not desire to be limited to this specific construction, since variations in respect to it may be made.

In operation by taking hold of the handle 9, the lower edge of the door is swung outward and upward and then pushed inward into an open position, and when it is desired to close the door, it is pulled outward by means of the handle 9 when the hook 8 catches on the lower wall of the slots 6, thus stopping the outward movement of the door and sustaining it in its vertical closed position.

By means of the above construction a very simple and cheap arrangement is provided for making a door that can be operated in the manner described.

Having thus described my invention, what I claim and desire to secure by Letters Patent is:—

1. A sliding door for stoves and the like, comprising a door-frame having openings, a door having its edges overlapping the frame and adapted to pass through the said openings, the top edges of the overlapping portion of the door adapted to engage with the wall of the opening when the door is in a closed position.

2. In a stove having a frame provided with openings, a door having a portion overlapping the frame and adapted to slide through the said openings, a tray supported above the door, a handle at the lower edge of the door, the upper ends of the overlapping portion of the door adapted to catch on the wall of the openings when the door is in a closed position, and a handle adapted to

strike the tray and limit the opening of the door.

3. A sliding door for stoves, comprising a stove frame having openings in its edges, a door having its edges overlapping the frame, the overlapping part of the door passing through the said openings and the upper ends of the overlapping portion bent downward, whereby the door is limited in its outward movement and sustained in its vertical closed position.

4. A sliding door for stoves and the like, comprising a stove-frame having slots with open inner ends, the door having its edges overlapping the stove-frame, and the upper ends of the overlapping portion bent inward and downward, for the purpose described.

5. A sliding door for stoves and the like, comprising a stove-frame having slots with open inner ends, a stove door having vertical L-shaped portions at its ends, one leg of the L-shaped portion extending beyond the other leg and bent inward and downward for the purpose of stopping and sustaining the door in its closed position.

6. A sliding door for stoves and the like, comprising a frame having horizontal slots with open inner ends, a door having its vertical side edges overlapping the frame and the top ends of the overlapping part bent inward and downward and the top edges of the center of the door also bent inward and downward to provide a finish for the door in its closed position and strengthening the center of the door.

In testimony whereof I hereunto affix my signature.

FREDERIC G. NICOLAUS.
